COMBINED TAPE DISPENSER AND CUTTER THEREFOR

Frank C. Simon, 741 E. Grandview, Sierra Madre, Calif.

Filed Oct. 22, 1965, Ser. No. 87,800

Term of patent 14 years

(Cl. D74—1)

FIGURE 1 is a perspective view of a combined tape dispenser and cutter therefor embodying my new design;

I claim:

The ornamental design for a combined tape dispenser and cutter therefor, substantially as shown.
